MEANS FOR DISCHARGING FLUID PRESSURE CONTAINERS

Scott E. Allen, Los Angeles, Calif., assignor, by
mesne assignments, to C-O-Two Fire Equipment
Company, Newark, N. J., a corporation of
Delaware

Application January 10, 1933, Serial No. 650,957

33 Claims. (Cl. 169—11)

The present invention relates to means for discharging fluids from containers and more particularly to the discharge of cylinders or the like containing fluid under high pressure such, for instance, as liquefied carbon dioxide.

The invention has for a specific object to provide an improved discharge head for a cylinder containing high pressure fluid in which the fluid released from the cylinder or from an associated cylinder will assist in operating the discharge head, thereby rendering the discharge head in part self-energizing.

In a copending application, Serial No. 349,150, filed March 22, 1929, a self-energizing fluid actuated discharge head is described. However, the present invention differs therefrom in that the discharge head is normally inoperative by fluid pressure and cannot be actuated until after an initial manual operation. This precludes the possibility of the discharge of a cylinder by an accidental discharge of an associate cylinder.

Another object of the present invention is to provide a discharge head adapted for manual operation, but in which after an initial partial release of fluid from the container such manual operation may be aided by the fluid released. The manual operating means may serve merely to release power with which to complete operation of the discharge mechanism. At the same time, however, the manual means may be relied upon to effect the entire release or discharge of the fluid without the aid of the fluid pressure if for any reason there should be a failure of the fluid pressure operated means.

My invention is particularly adapted for use in fire extinguishing systems employing a battery of cylinders containing liquefied carbon dioxide or other fluid extinguisher maintained at high pressure. Usually, the cylinders are closed by sealing disks which must be punctured or ruptured to release the fluid, but it requires considerable effort to puncture each disc and the puncturing of the disk of a battery of cylinders simultaneously may call for a greater effort than a person can normally exert. This difficulty has been overcome in the past by using one or two cylinders as master cylinders which may be discharged manually and providing a separate mechanism energized by the pressure of the fluid from the master cylinders to set off the rest of the battery. Such auxiliary power mechanism adds to the expense of an installation; it necessitates the actuation of a particular discharge head to effect discharge of the battery; also if the master cylinder has to be disconnected for

refilling or repair the whole system is thrown out of operation until the cylinder is restored to the system. Another system is described in Patent No. 1,827,723, wherein actuation of the discharge head of any one cylinder will result in discharge of all the rest of the cylinders. Each cylinder is provided with a fluid pressure operated discharge head and all the cylinders are interconnected so that when fluid under pressure is discharged into the system all of the cylinders will be discharged. In the present invention also a fluid-actuated means is provided in each discharge head and all the heads are connected to a common delivery line, but accidental discharge of any cylinder will not set off the rest because a manual operation of each discharge head is necessary before it can be set off automatically.

A further object of my invention is to provide a common manual control for a battery of cylinders in which one or more cylinders may be set off prior to the others, but in which the latter will be prepared for operation by discharge of fluid from the first actuated cylinder.

Another object of the invention is to provide a system of the character described in which any cylinder of a battery may be disconnected without affecting the operativeness of the system as a whole.

Another object of the invention is not only to prevent discharge of a battery of cylinders when one cylinder is accidentally discharged but to prevent dangerous explosion in case of breakage due to careless handling of the cylinder. The weakest part of the cylinder is at the point where the discharge head is attached thereto. Occasionally when a cylinder falls over or is dropped a break occurs at this point. The fluid then discharges with explosive force sometimes resulting in serious damage.

It is a specific object of my invention to provide a check valve which is normally inoperative to check discharge from the cylinder, but which will come into operation when the discharge head is broken off the cylinder.

Other objects and advantages of my invention will appear in the following description of a preferred embodiment and modification thereof and thereafter the novelty and scope of the invention will be pointed out in the claims.

In the accompanying drawings;

Figure 1 is a plan view of a battery of cylinders containing highly compressed fire extinguishing fluid;

Fig. 2 is a fragmental view in front elevation of one of the cylinders and its discharge head with

portions thereof in section showing a cutter and a safety valve in normal position;

Fig. 3 is a fragmental view in section corresponding to a portion of Fig. 2 but showing the cutter in cutting position;

Fig. 4 is a top plan view of the safety valve;

Fig. 5 is a fragmental view in vertical section showing a slightly different form of cutter head;

Fig. 6 is a fragmental view, largely in vertical section, illustrating another form of cutter;

Fig. 7 is a fragmental view in perspective of the cutter shown in Fig. 6;

Figs. 8 to 10 inclusive are plan views showing successive steps in the cutting of a sealing disk by the cutter illustrated in Figs. 6 and 7; and

Fig. 11 is a plan view of the sealing disk after a flap has been cut out of the disk and showing the flap partly bent upward by fluid pressure.

The cylinders 10, shown in the drawings, are of the usual form adapted for storage of highly compressed fire extinguishing fluid such, for instance, as liquefied carbon dioxide. The neck 11 of each cylinder has a neck stem 12 threaded therein. This stem has an axial bore 13 therethrough which is normally closed by a sealing disk 14. The disk is seated on a shoulder 15 in the bore and is held to its seat by a tubular plug 16 threaded into the upper end of the neck stem. The stem 12 carries the usual valved fitting 17 for filling the cylinder. Threaded into the lower end of the stem 12 is the usual siphon tube 18 which extends to the lower end of the cylinder so as to discharge the liquefied gas under pressure of gas in the upper portion of the cylinder. Mounted on the upper end of the stem 12 is a discharge head which will be described presently.

Since occasionally such discharge heads are broken off by careless handling of the cylinders, I provide a safety valve to check discharge of the cylinder. The weakest part of the stem, where breakage takes place, is at a point just above the neck 11 of the cylinder, and it is below this point that the safety valve is provided. While check valves of various forms might be used I prefer the structure shown in the drawings.

Within the zone of the neck 11 the bore of the stem 12 is enlarged to form a valve chamber 20. A disk valve 21 is provided in this chamber, and normally rests on the upper end of the siphon tube 18. On the disk are formed guide vanes 22 which project into a portion 23 of the bore above the valve chamber. When the valve is raised to permit discharge of the fluid from the cylinder, these vanes strike a shoulder 24 in the bore before the disk rises sufficiently to engage a shoulder 25 forming the upper limit of the valve chamber, so that the fluid may flow freely around the disk valve and on up through the bore of the neck stem 12. However, should the stem 12 be broken off the break would occur below the shoulder 24, since this is above the weakest part of the stem. Such breakage would permit the disk to move outward far enough to seat against the shoulder 25 and check the outflow of fluid. Normally this would seal the cylinder against discharge but it is advisable to provide some means permitting slight discharge so that if the fluid should be expanded by heat it would not develop sufficient pressure to burst the cylinder. Because the fit between the disk 21 and the shoulder 25 is not a perfect one, a certain amount of leakage may take place. However, I prefer to provide a port

27 through the disk which will be small enough to permit a controlled discharge of the cylinder. This port also serves to admit fluid into the cylinder when it is being filled, since during the filling operation the disk valve 21 will normally be 5 seated on the top of the siphon tube 18.

The discharge head above referred to comprises a main body 30 which is attached to the upper end of the stem by a coupling nut 31. The body 30 is formed with a lower chamber 32 into 10 which the fluid discharges when the sealing disk 14 is ruptured and connected to this discharge chamber is a discharge pipe 33.

In the upper part of the body 30 is formed a cylinder chamber 34 in which fits a piston 35. 15 The latter is journaled on a stem 36, being held between a shoulder 37 on the stem at one side and a nut 38 on the other side. This nut, however, is threaded on the stem against a shoulder 39 so that it may be tightened without gripping 20 the piston sufficiently to prevent turning of the latter freely on the stem. A plug 40 closes the upper end of the cylinder. The stem 36 is journaled in the plug and is provided at its outer end with a handle or operating arm 41. 25

The stem 36 is threaded through the wall 42 separating chamber 34 from chamber 32, and swiveled on a reduced end portion 43 of the stem is a hollow cylindrical cutter 44. This cutter is provided at its lower end with an annular cutting 30 edge inclined from normal to the axis of the cutter and interrupted at the inner side by a recess 45. The latter provides a shoulder about which the flap 46 cut out of the sealing disk by the cutting edge, may be bent by pressure of the fluid 35 discharge from the cylinder. The flap consequently is not detached from the disk but remains integrally hinged thereto and is flattened against the inner surface of the annular cutter by the fluid discharge. An annular shoulder 47 40 on the cutter is adapted to engage the plug 16 as a stop and prevents the possibility of detaching the flap. Near its upper end the cutter is provided with ports 48 through which the fluid may discharge into the chamber 32 and thence 45 into the discharge pipe 33.

The piston stem 36 is formed with an axial duct or bore 49 which terminates at its upper end in a transverse bore 50 opening into the cylinder chamber 34 above the piston 35. The lower end 50 of the bore 49 is closed by a screw 51, the head of which serves to retain the tubular cutter upon the end portion 43 of the piston stem. There is another transverse bore 52 which intersects the bore 49 and which opens through the threaded portion of the stem. The bore 52 is normally disconnected from the discharge chamber 32 when the stem is in the raised position shown in Fig. 2, but when the stem is screwed down and the cutter is about to penetrate the sealing disk the bore or port 52 is uncovered, permitting fluid to pass from the discharge chamber 32 into the cylinder chamber 34 above the piston. The lower end of the cylinder chamber is provided with an air vent 53. 65

It will be evident that when the handle 41 is operated to force the cutter downward there will be no resistance to movement of this cutter until it strikes the cylinder disk 14, and thereafter, as soon as the disk is slightly punctured, fluid escaping into the discharge chamber will pass through the transverse bore 52, now uncovered, into the axial bore 49 and thence through transverse bore 50 into the cylinder chamber 34, and the fluid acting on the piston will force down the 70 75

cutter so as to complete the cutting open of the flap. The cooperating threads on the piston stem and in the wall 42 are of such steep pitch angle that movement of the handle 41 through a small arc will carry the cutter from normal position shown in Fig. 2 to the end of its cutting stroke as shown in Fig. 3. Also because of the steepness of the threads, the pressure of the fluid released from the cylinder will be sufficient to force the piston 35 downward. As the piston moves downward in the chamber 34 air under the piston is vented through the port 53.

While the piston 35 might be fixed to the stem 36 I prefer to have it journalled thereon so that frictional engagement between the piston and cylinder wall will not retard the rotation of the stem. Obviously, because of the smaller bearing surface of the piston on the stem than the bearing surface of the piston on the cylinder, there will be less resistance to overcome when turning the stem to feed the cutter downward and the piston may slide in the cylinder without rotating.

The discharge pipe 33 is connected by a T-fitting 55 to the main delivery pipe 56. In a fire extinguishing system comprising a plurality of cylinders 10 it is desirable to provide a check valve between each discharge chamber and the delivery pipe, and I prefer to provide this check valve in the T-fitting 55. This T-fitting comprises a pair of aligned threaded ports 57 and 58 to receive sections of the delivery pipe 56 and a transversely disposed port 59 into which a nipple 60 is threaded, the latter being coupled to the discharge pipe 33. Opposite the port 59 there is an enlarged opening in the fitting which is normally closed by screw plug 62. Surrounding the port 59 there is a valve seat 63 on which normally rests a disk valve 64. The latter is confined against lateral displacement by lugs 65. To guide the disk valve when it is raised from its seat fingers 66 are formed on the disk which enter a recess 67 in the screw plug 62. When there is a discharge of fluid through the pipe 33 the disk valve is lifted off its seat and the fingers 66 as well as the lugs 65 prevent the disk from shifting laterally, and also insure return of the valve to its seat when the fluid pressure on the under side of the valve drops.

It is frequently desirable to remove a cylinder to test the same or to refill it if the quantity of fluid therein has been reduced materially through leakage. At such times it is important to maintain the system operative, as a fire might occur while the cylinder was disconnected. The disk valve 64 is provided to permit of such disconnection without disturbing the fire protection system. In other words, when the cylinder is disconnected from the discharge pipe 33 or the pipe itself is disconnected from the T-fitting, fluid may be introduced into the discharge line 56 without material loss because the port 59 is cut off by the disk 64. However, it is necessary to provide for a certain amount of discharge from the main discharge line through the disk valve 64 for a purpose which will be explained presently and to this end I provide a port 68 in the disk.

In Figure 1, I show a battery of cylinders each provided with a discharge head of the same type as that shown in Fig. 2 and each having a discharge pipe which is connected to a delivery pipe (not shown). The handles 41 of the discharge heads are connected to a common operating rod or cable 70, so that they may all be pulled simultaneously. However, to penetrate all of the cylinder disks at the same time would require a

greater effort than could be exerted manually by a normal individual. I, therefore, arrange the battery of cylinders so that one cylinder will be discharged ahead of the others and the fluid released from this first cylinder will assist in causing the puncturing of the disks of the rest of the cylinders. This may be done by setting one of the cutter heads with its cutter nearer the cylinder disk than are the cutters of the other cylinders. The simplest way of effecting such advance operation is to give one of the handles 41 a slight lead over the rest. Thus, in Figure 1 the handle 41 of the cylinder A at the extreme right of the battery is angularly displaced toward the right with respect to the other handles so that when the rod or cable 70 is pulled the cutter of the cylinder A will penetrate its sealing disk before the other cutters have penetrated their sealing disks. As soon as fluid is released from the cylinder A it will enter the delivery line 56 and will pass into the discharge chambers of all of the other cylinders by way of their respective discharge pipes 33. The volume of fluid entering said discharge chambers will be comparatively small, being restricted by the size of the ports 68 in the disk valves controlling said discharge pipes. The fluid will then serve to actuate the pistons of said other cylinders as soon as their piston stems 36 have been manually screwed downward sufficiently to uncover their transverse bores 52. As a result of this arrangement, the only effort necessary to set off a battery of cylinders is that required to puncture slightly the sealing disk of cylinder A and to condition the discharge heads of the rest of the cylinders 35 for operation by screwing down their piston stems sufficiently to uncover their ports 52. Thereafter puncturing of the sealing disk of cylinder A will be effected by the energy of its own fluid and such fluid will furnish the energy necessary to puncture the sealing disks of all of the rest of the cylinders. The reason for the port 68 will now be apparent. It permits fluid from the delivery line to pass into the discharge head of the cylinder it controls, and at the same time should it be necessary to disconnect the cylinder the leakage of fluid through said port would not be sufficient materially to effect delivery of fluid to the discharge end of the delivery line. If necessary two or more of the arms 41 may be set to cause initial discharge of the cylinders with which they are associated.

In Fig. 5, I show a slightly modified form of discharge head. This structure differs from that shown in Figs. 2 and 3 mainly in the fact that the piston stem is not rotated to effect cutting of the sealing disk.

The discharge head 71, in Fig. 5, is similar to the head 30, having a stem 72 with a tubular cutter 73 connected to the lower end thereof. A piston 74 connected to the stem 72 operates in a cylinder chamber 75 formed in the upper portion of the body 71. The stem 72 projects through a plug 76 closing the upper end of the cylinder, and the projecting end of the stem is provided with a head 77. A spring 78 is fitted under the piston 74 and serves to hold the cutter normally in the raised position shown.

The plug 76 is provided with a threaded boss 79 on which is screwed a cap 80. A lever is pivoted to the cap and has one arm 81 within the cap and another arm 82 projecting outwardly through an opening in the cap. A roller carried by the inner arm 81 bears upon the head 77. The arm 82 may serve as a handle for direct

5 manual operation or it may be connected to a rod or cable as is the arm 41 in Fig. 1. By pulling the arm 82 the stem will be depressed, causing the cutter 73 to puncture the sealing disk.

5 As soon as fluid is released from the cylinder it will force its way through a lateral port 84 in the stem and thence through an axial bore 85 and lateral port 86 into the upper part of the cylinder 75. The fluid pressure will then complete the

10 depression of the piston. Also when the stem is depressed sufficiently to uncover port 84 the apparatus will be conditioned for operation by fluid introduced into the discharge head from another cylinder.

15 Heretofore in systems employing fluid actuated discharge mechanism and in which the fluid discharged from any one of a battery of cylinders would actuate the rest of the battery, it has been necessary to provide a safety disk, as disclosed in

20 said copending application Serial No. 349,150. This safety disk is adapted to rupture at a pressure lower than that which the sealing disk can support. Hence, if, due to a rise in temperature, the pressure of the fluid in the cylinder

25 should rise above a safe limit the safety disk would give way, relieving the pressure. This safety disk protects the sealing disk, for if the latter were to be ruptured by a rise of fluid pressure in the cylinder the fluid would discharge

30 into the delivery line and would set off the entire battery of cylinders. With my present invention the safety disk may be dispensed with and the sealing disk may serve as a safety device, because no harm will result from such rupture.

35 The contents of the cylinder will discharge into the line but other cylinders connected to the line will not be discharged by the fluid pressure in the line because the duct in each discharge head leading from the discharge chamber to the

40 cylinder chamber thereof will be closed.

It will be noted that the siphon tube 18 is virtually suspended in the container by threading its upper end into the neck stem 12. I have found that if the threaded part of the siphon tube extends below said stem the tube may be snapped off by a sudden jolt, such as would occur if the container were knocked over or dropped on its side. To avoid this danger the stem is counter-bored as indicated at 81, providing a tight fit for the stem below the threaded part thereof, thereby materially strengthening the connection between the tube and the stem, because at the point of greatest stress, namely along the line where the tube emerges from the stem, said tube is not weakened by the cutting of a thread therein.

The cutter shown in Figs. 2, 3, and 5, is designed to operate without turning, the flap in the sealing disk being cut out by direct pressure in the axial direction. In Figs. 6 and 7, I show another form of cutter which turns while engaging the disk so that it will first score and then shear the disk instead of merely punching it. However, this scoring and shearing action takes place through an angle of less than 360 degrees so as to leave a substantial part of the flap cut out integrally attached to the body of the disk.

In general the discharge head shown in Fig. 6 is similar to that shown in Fig. 2 and like parts are therefore indicated by the same reference numerals. The principal difference however is that the cutter is fixed to the stem of the piston 35. The stem is indicated in Fig. 6 by the reference numeral 36a and is threaded into a socket

formed in the upper end of the cutter 90. As shown more clearly in Fig. 7, the cutter 90 is tubular and is formed with an arcuate cutting edge 91 of considerably less than 360 degrees in extent, which cutting edge lies in a plane 5 normal to the axis of the tubular cutter instead of being inclined thereto as in the cutter 44. This cutting edge 91 is interrupted on one side by a shallow recess forming a blunt shoulder 92 which is stepped out of the plane of the cutting 10 edge 91. The cutter is also provided with an annular shoulder 93 which is adapted to engage the tubular plug or sleeve nut 16 to limit downward movement of the cutter and prevent the shoulder 92 from being forced through the disk. 15

The stem 36a is provided with a threaded portion 42a which is threaded into the main body of the discharge head and there is an axial bore 49a in the stem which communicates at one end with a transverse bore 50a opening into the cylinder chamber above the piston while another transverse bore 52a opens through the threaded portion 42a and is closed when the parts are in the normal position shown in Fig. 6. The lower end of the axial bore 49a is closed by the bottom wall 90a of the socket into which the stem is threaded. It will be understood, of course, that the cutter is provided with openings 94 through which gas liberated from the container may escape into the chamber 32 and thence pass out through the tube 33 to the delivery line.

The operation of this cutter is as follows:

The piston stem 36a carries the operating arm 41 which is attached to the pull rod or cable 70, as in Fig. 1, and the parts are so arranged that this arm turns through an angle of approximately 90 degrees in moving the cutter from the normal position illustrated to complete cutting position. In the latter position the shoulders 93 engage the sleeve nut 16 and prevent further longitudinal movement of the cutter. Fig. 8 illustrates the initial position of the cutter in broken lines on the sealing disk 14. The shoudered portion 92 is here shown as extending through an angle of 135 degrees, while the sharpened edge 91 embraces an arc of 225 degrees. While the arm 41 is moving initially through an angle of about 45 degrees the cutter is being advanced toward the disk 14 until it comes into engagement therewith. During this interval no cutting takes place but the piston stem is moved in axial direction sufficiently for the bore 52a to be uncovered, so that if any fluid has been admitted into the chamber 32 through the pipe 33, it will find its way through the stem to the top of the piston chamber 34 and will then act upon the piston either to assist in further movement of the arm 41 or else to assume the entire task of forcing the piston the rest of the way down to complete cutting of the disk. Fig. 9 illustrates the position of the cutter after the arm 41 has moved through the initial 45 degrees and the cutter is just beginning to score the disk. As the arm is moved through the second 45 degrees the cutter begins to bite into the disk, and eventually shears through the disk until it finally reaches the position indicated by broken lines in Fig. 10. When the latter position is reached, the disk will have been cut and scored through an angle of 270 degrees and the pressure of the fluid in the cylinder 10 will force out the cut portion of the disk 46. Fig. 11 shows the flap in an instantaneous position as it is being forced upward into the tubular cutter. The 75

force of the compressed gas in the cylinder is sufficient to tear the flap along the scored parts and to bend it up about the shoulder 92 as an anvil, flattening the flap against the inner cylindrical wall of the cutter.

As described in co-pending application Serial No. 349,150, filed March 22, 1929, it is necessary to provide a shoulder about which the flap may be bent as otherwise the sudden bursting out of the flap under pressure of the gas is likely to tear the flap free of the disk and carry it into the discharge head. Such a loose piece of metal might jam and obstruct the ports 94, or it might actually be blown out to the discharge point and in case of a fire in electrical machinery it might do considerable damage by providing a short circuit. As described in said application, the danger of tearing the flap loose is obviated by providing the shoulder 92 which comes substantially into engagement with the disk at the time when the flap is burst out of the disk.

The advantage of using a cutter of this type over that shown in Fig. 2 is that less effort is required to score and shear the flap out of the disk than to actually punch the flap out of the disk.

In the particular design of cutter illustrated, the combined shearing and scoring takes place from the point A to the point B, Fig. 10, leaving an uncut and unsheared hinge portion of about 90 degrees in extent. Actually in practice the tearing action may extend a little beyond the points A and B but a substantial portion of unscored and uncut metal will be left to form the hinge for the flap 46.

While I have described a preferred embodiment of my invention and certain modifications thereof it will be understood that these are to be taken as illustrative and not limitative of my invention and that I reserve the right to make such changes in form, construction and arrangement of parts as fall within the spirit and scope of the following claims.

I claim:

1. A device for opening a fluid container, comprising a fluid pressure actuatable means for opening the container, an external supply of actuating fluid under pressure for actuating said means, said means being normally in condition preventing operation thereof by said actuating fluid, and conditioning means for conditioning the first-named means to permit operation thereof by said fluid.

2. A device for opening a fluid container comprising an opening member, means actuatable by fluid pressure upon a surface thereof for operating the opening member, conduit means for supplying actuating fluid from an outside source to said surface, said fluid actuatable means being normally in a position interrupting flow from the conduit means to said surface but movable to a position to permit such flow to said surface so as to operate the fluid actuatable means, and a controller for moving said means to the latter position.

3. A device for opening a fluid container, comprising an opening member, an actuator movable by fluid pressure to operate said member, an external supply of actuating fluid under pressure for operating the actuator, the actuator in its normal position being operatively inaccessible to said actuating fluid, and means for moving the actuator into a position in which it will be operatively accessible to said actuating fluid.

4. A device for opening a container holding fluid under pressure, said device comprising an

opening member, an actuator movable by fluid pressure to operate the opening member to release the fluid from the container, an external source of fluid under pressure, a connection for supplying fluid released from the container and/or fluid from said external source to operate said actuator, the latter being normally in a position closing communication through said connection but being movable to a position to establish such connection, and means for moving the actuator to the latter position.

5. A discharge head for a container holding fluid under pressure and closed by a sealing disk, said head comprising a body formed with a discharge chamber and with a cylinder chamber, a member in the discharge chamber for rupturing the disk, a piston in the cylinder chamber, means operatively connecting the member and the piston, a connection for leading fluid from the discharge chamber into the cylinder chamber to depress the piston and operate the rupturing member, said connection being positively closed to passage of fluid therethrough until the piston has been depressed to a predetermined extent, and means for depressing the piston.

6. A discharge head for a container holding fluid under pressure and closed by a sealing disk, said head comprising a body formed with a discharge chamber and a cylinder chamber, a piston in the cylinder chamber having a stem projecting into the discharge chamber, a member for rupturing the disk connected to the stem in the discharge chamber, the stem having a passage therein opening at one end beyond the piston and normally closed at the other end but opening into the discharge chamber only when the piston has been depressed to a predetermined extent, and auxiliary means for depressing the piston.

7. A discharge head for a container holding fluid under pressure and closed by a sealing disk, said head comprising a body formed with a discharge chamber and a cylinder chamber separated by an intervening wall constructed and arranged to prevent passage of fluid between the chambers, a stem threaded through said wall, a member for rupturing the disk located in the discharge chamber and connected to said stem, a piston fitted in the cylinder chamber and connected to the stem, the coacting threads on the stem and wall being of such pitch that pressure applied on the piston will move the stem axially, the stem being formed with a duct opening at one end above the piston and normally closed at the other end by said wall but adapted to communicate with the discharge chamber when the stem is turned angularly to a predetermined extent, and means for turning the stem angularly.

8. A discharge head for a container holding fluid under pressure and closed by a sealing disk, said head comprising a body formed with a discharge chamber and a cylinder chamber separated by an intervening wall constructed and arranged to prevent passage of fluid between the chambers, a stem threaded through said wall, a member for rupturing the disk located in the discharge chamber and connected to said stem, a piston fitted in the cylinder chamber and rotatable on the stem but held against axial movement thereon, the coacting threads on the stem and wall being of such pitch that pressure applied on the piston will move the stem axially, the stem being formed with a duct opening at one end above the piston and normally closed at the other end by said wall but adapted to communicate with the discharge chamber when the stem is turned

76
65
75

angularly to a predetermined extent, and means for turning the stem angularly.

9. A discharge head for a container holding fluid under pressure and closed by a sealing disk, said head comprising a body formed with a discharge chamber and a cylinder chamber separated by an intervening wall constructed and arranged to prevent passage of fluid between the chambers, a stem threaded through said wall, a member for rupturing the disk connected to said stem in the discharge chamber, a piston in the cylinder chamber and rotatable on the stem but held against axial movement thereon, the stem being formed with a duct opening at one end above the piston and normally closed at the other end by said wall but adapted to communicate with the discharge chamber when the stem is turned sufficiently to rupture the disk, said stem projecting from the head, and means attached to the projecting end for angularly turning the stem, the pitch angle of the threaded connection of the stem with the wall being steep enough to permit depression of the piston by pressure of the fluid released upon rupturing the disk.

10. In combination a plurality of containers each holding fluid under pressure, a fluid pressure actuatable device associated with each container for effecting discharge of fluid therefrom, a conduit for supplying actuating fluid to the devices, said conduit being normally out of communication with each device, a controller for establishing communication with each of the devices, and means operated by said controller for supplying actuating fluid to said conduit.

11. In combination a plurality of containers each holding fluid under pressure, a common fluid discharge conduit for the containers, a fluid pressure actuatable device associated with each container for controlling discharge of fluid therefrom into the conduit, such devices being normally operatively out of communication with the conduit but which can be placed into communication with the conduit, an external source of fluid under pressure normally out of communication with the conduit, and a control means for establishing communication between said conduit and said source and for establishing operative communication between the conduit and each of said devices so as to supply actuating fluid thereto.

12. In combination a plurality of containers each holding fluid under pressure, an opening device for each container, a common fluid discharge conduit for said containers, an actuating element for each device, a common control for operating said elements, auxiliary actuating means actuatable by fluid pressure for operating each device, and a connection normally disconnected but adapted to establish communication between the conduit and each of said means upon initial operation of the device, one of the opening devices being adjusted for operation by said control in advance of the others, so as to discharge fluid into the conduit to operate said auxiliary actuating means and thereby assist in operating the opening devices.

13. In combination, a plurality of containers each holding fluid under pressure, an opening device for each container, a common fluid discharge conduit for said containers, a lever for operating each device, a common control interconnecting said levers, one of the levers being adjusted for advance operation with respect to the others, auxiliary actuating means actuatable by fluid pressure for operating each device, and a connection normally disconnected but adapted

to establish communication between the conduit and each of said means upon initial operation of said common control whereby fluid discharged into the conduit by operation of the opening device connected with the lever adjusted for advance operation will operate said auxiliary actuating means to assist in operating the opening devices.

14. In combination, a plurality of fluid containers, a discharge line, connecting means for detachably connecting each container to said line, fluid actuatable discharge means for controlling the discharge of each container into said line, means operable at will to admit fluid from the line to actuate each discharge means, and a check valve for each connecting means opening toward the line and constructed when in closed position to provide limited outflow from the line.

15. In combination, a plurality of fluid containers, a discharge line, connecting means for detachably connecting each container to said line, fluid actuatable discharge means for controlling the discharge of each container into said line, means operable at will to admit fluid from the line to actuate each discharge means, and a check valve for each connecting means opening toward the line, said valve having an orifice therethrough for the passage of fluid to actuate the discharge means.

16. In combination, a fluid container, means for controlling discharge of fluid therefrom, said container having a zone of weakness spaced inwardly from said means, and safety means for preventing uncontrolled discharge of fluid from the container should the latter be severed at said zone of weakness, said safety means being inoperative to prevent discharge from the container when the latter is intact.

17. In combination, a fluid container having a discharge port, closure means therefor, a valve seat spaced inwardly from the closure means, a check valve movable outwardly to engage the seat, the container having a circumferential zone of weakness between the seat and the closure means, and stop means disposed outwardly of said zone and adapted normally to prevent seating of the valve.

18. In combination, a fluid container having a discharge port, closure means therefor, a valve seat spaced inwardly from the closure means, a check valve movable outwardly to engage the seat, the container having a circumferential zone of weakness between the seat and the closure means, and stop means disposed outwardly of said zone and adapted normally to prevent seating of the valve, said valve having a constricted opening therethrough.

19. In combination, a fluid container having a discharge port and a filling port, a closure for each port, a pair of valve seats disposed inwardly from said ports, a valve disposed between said seats and normally bearing on the inner seat, the container having a circumferential zone of weakness between the outer seat and said ports, stop means disposed outwardly of said zone for preventing the valve from seating on the outer seat unless the container is severed at said zone, and by-pass means permitting limited flow past the valve when it is bearing on either seat.

20. A discharge head for a container holding fluid under pressure and closed by a sealing disk, said head comprising a body adapted to be connected to the container, a puncturing member constructed and arranged to be operated by longitudinal movement without rotation, an ac-

- tuator for advancing the member to puncture the disk, a threaded connection between the body and the actuator whereby the latter may be advanced by rotation with respect to the body, and 5 a swivel connection between the actuator and the member whereby said member may be operatively advanced without rotation.
21. A device for opening a fluid container, comprising an opening member, an actuator rotatable by application of fluid pressure to a surface thereof to operate the opening member, conduit means for supplying operating fluid to said surface, said actuator being normally in a position to interrupt communication of said fluid 10 to said surface but being movable to a position to establish such communication, and a controller for moving the actuator to the latter position.
22. A device for opening a fluid container, comprising an opening member, an actuator rotatable by application of fluid pressure to a surface thereof to operate the opening member, conduit means for supplying operating fluid to said surface, said actuator being normally in a position to interrupt communication of said fluid 15 to said surface but being rotatable to a position to establish such communication, and a controller for rotating the actuator to the latter position.
23. A device for opening a fluid container, comprising an opening member operable by axial movement, an actuator carrying said member and rotatable by application of fluid pressure to a surface thereof to operate said member, there 20 being a swivel connection between the opening member and the actuator, means for conducting fluid released from the container to said surface to rotate the actuator, said actuator being normally in a position to interrupt communication 25 of said fluid to said surface but being rotatable to a position to establish such communication, and a controller for initiating operation of the opening means and moving the actuator to the latter position.
24. A device for opening a fluid container, comprising an opening member operable by axial movement, an actuator carrying said member and rotatable by application of fluid pressure to a surface thereof to operate said member, there 30 being a swivel connection between the opening member and the actuator, means for conducting fluid released from the container to said surface to rotate the actuator, said actuator being normally in a position to interrupt communication 35 of said fluid to said surface but being rotatable to a position to establish such communication, and auxiliary means for moving said actuator to initiate operation of the opening member and condition the actuator for operation by the fluid 40 released by the opening member.
25. A device for opening a fluid container, comprising an opening member operable by axial movement, an actuator carrying said member and helically movable by application of fluid 45 pressure to a surface thereof to operate said member, there being a swivel connection between the opening member and the actuator, means for conducting fluid released from the container to said surface to move the actuator, said actuator being normally in a position to interrupt communication 50 of said fluid to said surface but being movable to a position to establish such operative communication, and a controller angularly operable to move the actuator to the latter 55 position and initiate operation of the opening means.
26. A discharge head for a container holding fluid under pressure and closed by a sealing disk, 5 said head comprising a body formed with a discharge chamber and with a cylinder chamber, a member in the discharge chamber operable by axial movement to rupture the disk, a piston in the cylinder chamber, a rotatable member connecting the rupturing member having a swivel 10 connection with the rupturing member and the piston, a connection constituting the sole means for leading fluid from the discharge chamber into the upper end of the cylinder chamber to depress the piston and rotate the connecting 15 member and thereby operate the rupturing member, communication between the chamber through said connection being interrupted when the connecting member is in its normal position but being established after the piston has been 20 depressed to a predetermined extent, and means for depressing the piston.
27. A discharge head for a container holding fluid under pressure and closed by a sealing disk, 25 said head comprising a body formed with a discharge chamber and a cylinder chamber, an intervening wall preventing passage of fluid between the chambers, a stem threaded through said wall, a member for rupturing the disk located in the discharge chamber and connected 30 to said stem, a piston fitted in the cylinder chamber and connected to the stem, the coacting threads on the stem and wall being of such pitch that pressure applied to the piston will move the stem axially, the stem being formed 35 with a duct opening at one end above the piston and normally closed at the other end by said wall but adapted to communicate with the discharge chamber when the stem is turned angularly to a predetermined extent, and means for 40 turning the stem angularly.
28. A discharge head for a container holding fluid under pressure and closed by a sealing disk, 45 said head comprising a body formed with a discharge chamber and a cylinder chamber, an intervening wall preventing passage of fluid between the chambers, a stem threaded through said wall, a member for rupturing the disk connected to said stem in the discharge chamber, a piston in the cylinder chamber rotatable on the 50 stem but held against axial movement thereon, the stem being formed with a duct opening at one end above the piston and normally closed at the other end by said wall but adapted to communicate with the discharge chamber when the 55 stem is turned sufficiently to rupture the disk, said stem projecting from the head, and means attached to the projecting end for angularly turning the stem, the pitch angle of the threaded connection of the stem with the wall being steep 60 enough to permit depression of the piston by pressure of the fluid released upon rupturing the disk.
29. In combination a plurality of containers each holding fluid under pressure, an opening 65 device for each container, a common fluid discharge conduit for said containers, a rotary actuator for each said device, a common control for operating the actuators, auxiliary actuating means actuatable by fluid pressure for operating 70 each device, and means providing a passage normally closed but arranged to open communication between the conduit and each of said means upon initial operation of the device, one of the opening devices being adjusted for operation by 75

- 5 said control in advance of the others, so as to discharge fluid into the conduit to operate said auxiliary actuating means and thereby assist in operating the opening devices.
- 5 30. In combination a plurality of containers each holding fluid under pressure, an opening device for each container, a common fluid discharge conduit for said containers, a rotary actuator for each said device, an arm for turning each actuator, a common control interconnecting said arms, one of the arms being adjusted for advance operation with respect to the others, auxiliary actuating means actuatable by fluid pressure for operating each device, and means providing 10 a passage normally closed but arranged to open communication between the conduit and each of said means upon initial operation of said common control, whereby fluid discharged into the conduit by operation of the opening device connected to the lever adjusted for advance operation will operate said auxiliary actuating means and thereby assist in operating the opening devices.
- 15 31. A releasing device for use in connection with a fluid container having an opening, a frangible closure member for the opening and a penetrating device adapted to penetrate said closure member by axial movement of the device to provide free passage through said closure, comprising, a body forming a chamber, fluid operated means in said chamber, a rotary stem having a swivel connection with said device and operatively connecting said means and said device, means for admitting fluid under pressure from 20 an outside source to a face of the fluid operated means to operate the same, including a passage
- 25

in the stem for delivering said fluid to said face and also to deliver fluid from the container to operate said fluid operated means when the fluid is released from the container by operation of the penetrating device, and means obstructing 5 flow through said passage in the normal position of the stem, said last mentioned means being rendered ineffective upon rotation of the stem.

32. In combination, a fluid container including a discharge fitting provided with means for controlling discharge of fluid from the container, 10 said fitting having a zone of weakness, and safety means for preventing uncontrolled discharge of fluid from the container should the fitting be severed at said zone of weakness, said safety 15 means being inoperative to prevent discharge from the container when the fitting is intact.

33. A discharge fitting for a container adapted to hold fluid under pressure and having an internally threaded discharge neck, said fitting having 20 an externally threaded tubular portion adapted to be screwed into said neck, a valve seat formed within said tubular portion and so located as to be within the neck when the fitting is screwed home therein, a check valve movable outwardly 25 to engage the seat, and a stop normally preventing the valve from engaging said seat, said stop being carried by the fitting at a point so located as to be beyond the outer end of the neck when the fitting is screwed home therein, whereby 30 should the fitting be broken off adjacent the outer end of the neck the stop will be rendered ineffective and the valve will be freed to check discharge of said fluid.
